UNITED STATES PATENT OFFICE

166,282

PURSE

Shizuko Tabata, San Mateo, Calif.

Application September 17, 1951, Serial No. 16,666

Term of patent 7 years

(Cl. D87—3)

To all whom it may concern:

Be it known that I, Shizuko Tabata, a citizen of the United States, residing at city of San Mateo, county of San Mateo, State of California, have invented a new, original, and ornamental Design for a Purse, of which the following is a specification, reference being had to the accompanying drawing, forming a part hereof.

I claim:

The ornamental design for a purse, as shown.
SHIZUKO TABATA.
